COMBINED TANK COVER AND CONTROL HOUSING

Omer E. Miller, 2316 Linden Ave.,
South Plainfield, N.J. 07080

Filed June 4, 1968, Ser. No. 12,196

Term of patent 14 years

Int. Cl. D23—01

U.S. Cl. D23—41

FIGURE 1 is a front elevational view of a combined tank cover and control housing showing my new design,
FIGURE 2 is a side elevational view of the combined tank cover and control housing of FIGURE 1,

FIGURE 3 is a rear elevational view,

FIGURE 4 is a top plan view, and

FIGURE 5 is a vertical sectional view taken on the line 5—5 of FIGURE 4.

The dotted lines shown in the drawings represent the body of a tank and are for illustrative purposes only.

I claim:

The ornamental design for a combined tank cover and control housing, as shown and described.
